UNITED STATES PATENT OFFICE.

OWEN R. DICKENS, OF SPRINGFIELD, MISSOURI.

BEER-PIPE CLEANER.

No. 885,452.

Specification of Letters Patent.

Patented April 21, 1908.

Application filed July 10, 1906. Serial No. 325,510.

To all whom it may concern:

Be it known that I, OWEN R. DICKENS, a citizen of the United States, residing at Springfield, in the county of Greene and State 5 of Missouri, have invented a new and useful Beer-Pipe-Cleansing Apparatus, of which the following is a specification.

This invention has relation to beer pipe cleaners, and it consists in the novel construction and arrangement of its parts, as 10 hereinafter shown and described.

The object of the invention is to provide an apparatus which may be easily and readily connected up with the coil of a beer pipe and 15 which when so connected may be operated so as to pass a cleansing fluid through the coil, which is followed by water which rinses the coil of said cleansing fluid, and after the water, air may be forced through the coil, whereby 20 the same is dried. The apparatus consists of two tanks connected together by pipes, as will be hereinafter explained; the cleansing fluid is placed in one tank from which it is forced through the coil of the beer pipe while 25 water is introduced into the other tank and is lead from the same into the first said tank and follows the cleansing fluid through the coil of the beer pipe. Compressed air is used as a medium for forcing the cleansing fluid 30 through the coil while the street pressure of the water is sufficient to carry the same through the coil.

In the accompanying drawings, the figure is a vertical sectional view of the apparatus 35 with parts in side elevation:

The apparatus consists of the tanks 1 and 2, which are connected together near their lower ends by the water pipe 3 which passes through the tank 1 and enters the lower portion 40 of the tank 2. The pipe 3 is provided with a valve 4. The pipe 5 connects the upper portion of the tanks 1 and 2 together. The tank 1 is provided with a removable cap 6, through the center of which the pipe 7 45 passes and terminates near the bottom of the tank 1. The said pipe 7 also passes through the top of the tank 2 and out through the side of the same near the bottom thereof. The pipe 7 is provided with a valve 8 which 50 is located between the tanks 1 and 2. The air pump 9 is connected with the pipe 10, which is provided with a branch 11 which connects with the tank 2 at a point intermediate of the top and bottom thereof; said 55 branch 11 is provided with a valve 12. Pipe 10 connects with the pipe 8 at a point out-

side of the tank 2 and is provided with a valve 13. The pipe 7 is adapted to be connected with the coil of the beer pipe to be cleaned.

The pipes 3, 5 and 7 holds the tanks 1 and 2 in proper relation to each other and in addition to performing the function of means for introducing liquid into the tank and for leading the liquid from the tank they serve as 60 structural connections between the tank and consequently the apparatus is compact and the parts are effectually braced.

The operation of the apparatus is as follows: The cap 6 is removed from the tank 1 and the cleansing fluid is placed therein, when the said cap is again applied to the top of the tank 1. The valves 8 and 13 are closed and the valve 12 is opened. Air is then pumped through the pipe 10 and branch 11 into the 65 tank 2, from whence it passes through the pipe 5 into the top of the tank 1. Thus the fluid in the said tank 1 is subjected to pressure. The valve 4 is then opened and water under 70 street pressure passes through the pipe 3 into the tank 2. The valve 12 is then closed. At this stage it will be observed that the liquid in the tanks 1 and 2 are separated by a cushion of air which fills the upper zones of the 75 said tanks. The valve 8 is then opened and the fluid in the tank 1 is forced up through the pipe 7 and through the beer coil. It is then followed by the cushion of air, which in turn is followed by the water which passes from the tank 2, through the pipe 5, into the 80 tank 1 and up through the pipe 7. Thus the cleansing fluid passes through the coil first and removes the foreign matter from the same and the water following the said fluid, will free the coil of the fluid. After sufficient 85 water has passed through the coil the valves 4 and 8 are closed, the valve 13 is opened and air is forced through pipe 10 and pipe 7 through the coil. Thus the coil is air dried.

Having described the invention, what is 90 claimed as new is:—

An apparatus such as described, comprising a plurality of tanks, a water pipe connecting with the lower portion of one tank and passing through the other tank and having 95 a valve, a pipe connecting the upper portions of the tanks together, a pipe entering the top of the tank through which the water pipe passes and terminating in the vicinity of the bottom thereof, said pipe passing 100 through the top of the other tank and emerging from the lower portion thereof and hav-

ing a valve located between the tanks, and
an air pipe connected with the last said pipe
and the last said tank and having a valve
located between the connection with the tank
5 and the last said pipe, and a valve located
upon the tank connection.

In testimony whereof I have signed my

name to this specification in the presence of
two subscribing witnesses.

OWEN R. DICKENS.
